UNITED STATES PATENT OFFICE.

LOUIS COURTOT, OF PARIS, FRANCE, ASSIGNOR TO AMERICAN RADIATOR COMPANY,
OF CHICAGO, ILLINOIS, A CORPORATION OF NEW JERSEY.

RADIATOR.

1,239,428.

Specification of Letters Patent. Patented Sept. 4, 1917.

Application filed January 13, 1914. Serial No. 811,794.

To all whom it may concern:

Be it known that I, LOUIS COURTOT, a citizen of the Republic of France, residing at Paris, in the Republic of France, have invented and discovered certain new and useful Improvements in Radiators, of which the following is a full, clear, and exact specification.

My invention and discovery relates to improvements in heating apparatus, and the same has for its object more particularly to provide a cast metal radiator formed of a plurality of units each of which comprises a transverse connecting member or manifold and a plurality of tubes each having a wall or metal line of predetermined thickness, and an external diameter so proportioned as to give a low value to the ratio of the annular cross-sectional area or the metal line relative to the external circumference or the external surface of a unit length of tube.

Further said invention has for its object to provide a radiator which has the same amount of radiating surface as the large and heavy radiators now in use, but which is about one-third or more smaller, about one-third or more lighter, and yet is materially more efficient.

Further said invention has for its object to provide a cast metal radiator which may be produced at a smaller cost per unit of radiating surface, which is more compact in form, more regular and uniform in shape, and which possesses a metal line much thinner than has heretofore been possible to employ in radiators of this type without impairing their capacity of resisting the pressure existing within the radiator. On the contrary their capacity of resisting shocks and pressure is materially enhanced.

Heretofore the radiator manufacturer, in aiming to increase the capacity or efficiency of the radiator, merely increased the size of the tube, varied the shape thereof or provided the same with fins, ribs, etc. This was done without taking into consideration either the internal diameter or the metal line of the tube or receptacle. The core volume and said metal line remained large in transverse area while the proportion of the metal line thereof relative to the external diameter of the tube as well as to the unit of external or radiating surface was

entirely unappreciated and therefore disregarded.

In constructing a radiator according to my invention I form the radiator section with a plurality of separated, thin-walled tubes whose metal line is of such predetermined or calculated thickness, and whose external diameter is of such proportion as to give a low value to the ratio which the annular cross-sectional area or metal line bears relative to the external surface per unit length of tube. By preference I form said tubes integrally with a base and a header whose walls are somewhat thicker than the walls or metal line of said tube.

Now, in the course of the development of my invention, I have discovered that in order to obtain the most efficient and economical results and the greatest efficiency per unit of radiating surface, the external diameter of the tube, the volume of the core and the thickness of the metal line in relation to a unit of radiating surface should be combined in a certain ratio or harmony in order to obtain an efficiency and economic result never heretofore obtained in a radiator.

Further I have discovered that the best results so far as efficiency are concerned are not obtained by merely increasing the area of the radiating surface, but high efficiency is best obtained when the weight of metal employed bears a fixed relation to a unit of radiating surface.

Further I have found that the maximum of efficiency per unit of radiating surface may be best obtained by using a plurality of properly proportioned tubes of small diameter.

Further I have found that by constructing a radiator incorporating the features herein set forth I am enabled to reduce the cost of construction materially, and yet produce a structure which overcomes the disadvantages of the cast metal type of radiator now in use, and which is in addition smaller, lighter, neater and more compact per unit of radiating surface. Further, I can produce a radiator which is capable of withstanding the same or greater internal pressure than the type heretofore made. The construction of a radiator incorporating the features above described permits of

the more accurate making of the cores. This minimizes the danger of shifting of the core in the process of molding, and also the displacing of the core during the operation of pouring the metal, and thus insures a more uniform and a more regular line of metal—one that is materially thinner than has heretofore been possible to obtain in work of this character.

10 To the attainment of the foregoing objects and ends my invention consists in the novel details of construction and in the combination, connection and arrangement of parts hereinafter more fully described and then 15 pointed out in the claims.

In the accompanying drawings forming part of this specification, wherein like numerals of reference indicate like parts,—

20 Figure 1 is a perspective view showing one form of radiator constructed according to and embodying my said invention;

Fig. 2 is an enlarged detail face view of a single detached radiator section;

Fig. 3 is an edge view thereof;

25 Fig. 4 is a transverse section taken on the line 4—4 of Fig. 2.

Fig. 5 is a detail vertical section taken on the line 5—5 of Fig. 2;

30 Fig. 6 is a detail transverse section showing a modified construction in which the tubes are connected by webs; and

35 Fig. 7 is a chart of curves for different thicknesses of metal lines expressing the relation existing between outside diameter of tube, external surface per unit length of tube, and annular cross-sectional area or metal line.

40 In said drawings 10 designates a radiator comprising a plurality of intermediate sections 11, 11, and end sections 12, 12, which latter are provided with supporting legs 13, 13.

45 Each radiator section is formed as an integral structural unit and consists of a narrow vertical base 15, a series of small tubes 16, 16, which by preference in the present instance I have shown as of equal diameter having their lower ends communicating with the interior of said base 15, and a header 17 50 which corresponds in outline and size with the base 15 and is formed integrally with the upper ends of the tubes 16, 16 which communicate therewith. By preference I make the walls or metal line of said base and header somewhat thicker than that of said tubes in order that the same may safely withstand the pressure of the heating agent.

55 The tubes 16, 16 are formed with an external diameter, a core volume and a metal line which bear a substantially fixed proportion or ratio to a unit of radiating surface, which relative proportions are readily determinable by means of the formula hereinbelow.

60 As the walls of said tubes 16, 16 possess a

very thin metal line, I provide each tube with reinforcing ribs 18, 18, which serve to protect said tubes against injury and to strengthen the same in order to withstand safely the bursting pressure of the heating 70 agent and at the same time serve to facilitate the pouring of the metal into the mold. By preference I provide each of said tubes upon its outer surface with four of said longitudinal ribs 18, 18 which are arranged equally 75 distant from each other and arrange certain of said ribs so that their outer edges shall be in the same vertical plane with the sides of said base 15 and said header 17.

As a result of extensive tests, I have found that by making the tubes 16, 16 of about 13 m. m. inside diameter, and the walls of said tubes about $2\frac{1}{2}$ m. m. in thickness a square foot of radiating surface will weigh about 3.96 pounds as compared with 6.50 pounds 80 for the same radiating surface in cast metal radiators of the type now generally used, and that even if the thickness of the tube were not reduced a material saving of metal would still be realized per unit of radiating 85 surface. The proper external diameter and the appropriate thickness of metal line which renders it possible to obtain this result may be readily determined by calculating the ratio existing between the area "A" of the 90 annular cross section of a round tube and the external surface "S" of a unit length 95 of tube. The said ratio $\frac{A}{S}$ is proportionate to the weight of sections having the same 100 radiating surface.

Let "D" represent the external diameter of the tube, "e" its thickness, and it is easy to ascertain or determine the ratio,

$$\frac{A}{S} = \frac{e(D-e)}{D}$$

105

In the chart illustrated at Fig. 7 I have plotted four curves which show the relation of the ratio $\frac{A}{S}$ to the outside diameter (D) 110 of tubes for the thicknesses (e) of metal lines of 2, 3, 4, and 5 m. m., respectively.

By examining said chart it will be readily obvious that with tubes 5 m. m. thick—this being the usual thickness at present,—the considered ratio varies from 4.5 to 4.16 when the external diameter varies from 50 to 30 m. m. When the external diameter is reduced to 20 m. m. the ratio drops to 3.75, and it falls still more rapidly in proportion as the diameter decreases; at the lower limit, i. e., when the internal diameter becomes

zero, the ratio $\frac{A}{S}$ is reduced to 2.5,—that is to say to nearly half of what it is for external diameters between 40 and 50 m. m.

120 If the thickness is 4 m. m. the ratio $\frac{A}{S}$ 125 (as will be clear from the curve for the 4 130

m. m. metal line) varies very little for diameters of 50, 40 and even 30 m. m. But below 25 m. m. the variation of the ratio $\frac{A}{S}$ is rapid and at the lower limit, when the internal diameter becomes zero—(outside diameter 8 m. m.), the value of $\frac{A}{S}$ is reduced to 2.00.

10 Heretofore the thickness of the walls or metal line in cast iron radiators has never been less than 4 m. m. If the thickness of the walls is reduced to 3 m. m.—on account of the reduction in the diameters, as explained above,—it will be seen that the ratio $\frac{A}{S}$ changes from 2.55 to 2.1 for tubes of 20 and 10 m. m. diameters respectively, and the lower limit becomes 1.5. And if the cores and molds are adjusted with sufficient precision to reduce the thickness to 2 m. m., the above ratios for some diameters of tubes will become 1.8 and 1.6 with a lower limit of 1.0. The economy in raw material thus realized over the radiators as now made would, therefore, be more than fifty per cent.

In the modified construction shown at Fig. 6, the tubes 16^a, 16^a, are shown connected by integral webs 16^b, 16^b, which form a radiator section presenting an unbroken surface.

From the foregoing it will be noted that by means of my invention the manufacturer is enabled to determine precisely the correct relative proportions which should exist in a radiator in order to produce the maximum efficiency, and at the same time he is enabled to reduce the size and weight of the radiator about one-third or more for a given area of radiating surface, and to produce a radiator which is neater in appearance, less expensive in construction and more efficient in operation than the radiators of the type now generally in use.

It is also to be noted that I have shown my radiator as formed with cylindrical tubes each provided with four reinforcing ribs which project laterally but a short distance beyond the outer walls of said tubes. It will be obvious, however, that the shape of the tube is immaterial as the same may be made of any form in cross section and be made with such number of longitudinal ribs as may be necessary to give the tube the required strength to withstand the bursting pressure of the heating agent circulating within the tube and that in some instances, depending upon the shape of said tubes, said ribs may be omitted.

Further it will be obvious that my inven-

tion, although herein shown as applied to the well-known loop tube type of radiator is, nevertheless, equally applicable to radiators of the so-called "wall" type.

65

Having thus described my invention, what I claim and desire to secure by Letters Patent is,—

1. A cast metal radiator section comprising a manifold, and a plurality of substantially cylindrical tubes in each of which the external diameter is not less than 15 m. m. and does not exceed 30 m. m., and in each of which the ratio of the annular cross-sectional area to the external surface per unit of length does not exceed $2\frac{1}{4}$, substantially as specified.

2. A cast metal radiator section comprising a manifold, and a plurality of substantially cylindrical tubes in each of which the external diameter is not less than 15 m. m. and does not exceed 30 m. m., and in each of which the thickness of the metal line is not less than 1.5 m. m. and does not exceed 3 m. m., substantially as specified.

85

3. A cast metal radiator section comprising a manifold, and a plurality of substantially cylindrical tubes each having an external diameter not less than 15 m. m. and not exceeding 30 m. m., and a metal line not less than 1.5 m. m. and not exceeding 3 m. m. in thickness, and in each of which the ratio of the annular cross-sectional area to the external surface per unit of length does not exceed $2\frac{1}{4}$, substantially as specified.

95

4. A cast metal radiator section comprising a manifold and a plurality of substantially cylindrical tubes, in which the ratio of the annular cross-sectional area to the external surface per unit of length is substantially constant for tubes having an external diameter not less than 15 m. m. and not greater than 30 m. m., substantially as specified.

100

5. A radiator section consisting of a unitary casting and comprising a manifold, and a plurality of substantially cylindrical tubes each having an external diameter not less than 15 m. m. and not exceeding 30 m. m., and a metal line not less than 1.5 m. m. and not exceeding 3 m. m. in thickness, and in each of which the ratio of the annular cross-sectional area to the external surface per unit of length does not exceed $2\frac{1}{4}$, substantially as specified.

110

Signed at Paris, France, this 27th day of December, one thousand nine hundred and thirteen.

LOUIS COURTOT.
